[57] CLAIM

The ornamental design for a bat in which a game player's hand is inserted, as shown and described.

DESCRIPTION

FIG. 1 is a top perspective view of a bat in which a game player's hand is inserted, showing our design; and FIG. 2 is a top perspective view thereof from the side opposite that shown in FIG. 1. The underside which is not shown in FIGS. 1 and 2, is flat and plain.
